COMPACTION APPARATUS

Wylie M. Lafferty, New Philadelphia, Ohio, assignor to United States Concrete Pipe Company, Pittsburgh, Pa., a company of Pennsylvania
Original application May 3, 1961, Ser. No. 107,411, now Patent No. 3,151,870, dated Oct. 6, 1964. Divided and this application May 11, 1964, Ser. No. 374,868
4 Claims. (Cl. 25—39)

This application is a division of my copending application Serial No. 107,411, filed May 3, 1961, now Patent No. 3,151,870, granted October 6, 1964.

This invention relates generally to bell and spigot concrete pipe and has specific reference to an apparatus for manufacturing tamped concrete pipe having reinforced bell ends, together with a new and improved product.

Bell and spigot concrete pipe is formed as a unitary structure having spigot and bell ends. The spigot end has an interior wall which has the same diameter as the shank or body of the pipe, and an exterior wall, which has the same diameter as the pipe shank or which may be tapered. The bell end has interior and exterior diameters, which are larger than those of the spigot end, so that when the spigot end of an adjacent pipe is disposed within the bell end, as the pipe sections are assembled together the joint therebetween permits for substantially uninterrupted fluid flow within the pipe, by precluding the necessity of constricting the interior pipe diameter at the joint. When the exterior wall of the spigot end is tapered the interior of the bell end is tapered complementary thereto.

The interior diameter of the bell end of the pipe is, therefore, greater than the interior diameter of the pipe shank by an amount equal to or slightly greater than twice the thickness of the pipe wall at the spigot end and the exterior diameter of the bell end is sufficiently large to provide a bell end wall having the desired structural strength.

For years it has been common to produce cast bell and spigot concrete pipe by using suitable metal, wooden or other forms, pouring the concrete therein, allowing sufficient time, up to 24 hours or more, for the concrete to set and then removing the pipe from the forms and permitting it to cure.

This process requires that the forms be used continuously for a period of 24 hours or more to produce a single length or section of pipe and a great many forms are necessary, therefore, in order to manufacture a relatively few sections of pipe. The process is, accordingly, slow and expensive in use and practice. The shank of cast concrete pipe could be and frequently was reinforced along its length by wire mesh or other means.

Subsequently, it has become more common to provide tamped concrete pipe.

Tamped bell and spigot concrete pipe is also produced by the use of molds or forms of suitable size, shape and material. This process, however, utilizes an extremely viscous concrete slurry, having only about 6 percent moisture, or just slightly more than that necessary for hydration of the concrete. As the viscous concrete slurry is poured into the form, it is repeatedly tamped or impacted, automatically, by mechanical means, so as to compact the concrete to increase its density and thereby its strength and utility.

With tamped concrete pipe the forms may be removed substantially immediately upon completion of the pouring, as the concrete sets at once, using substantially all of the moisture present in the slurry to hydrate and the newly formed concrete pipe immediately has sufficient strength to maintain its own shape and form while curing even though unsupported by the forms necessary for pouring.

Tamped concrete pipe has also been customarily manu-

2

factured with reinforcing wire or mesh in the spigot end and pipe shank.

However, production problems, incident to forming the bell end of tamped concrete pipe have effectively precluded providing satisfactory metal reinforcement for the bell ends. Accordingly, it has been common to strengthen the bell end of concrete pipe by making the walls thereof of greater thickness than the walls of the pipe section generally and of the spigot end in particular.

This has not been entirely successful, however, and the bell end of a concrete pipe section has been the weak portion of the structure. Pipe failures and breakage, both during and after installation, have occurred more frequently at the bell end than at any other part of the pipe section.

Accordingly, it has been found desirable to provide bell and spigot concrete pipe having reinforced bell ends, but the apparatus and method commonly used for manufacturing tamped bell and spigot concrete pipe is such that reinforcement of the bell end has precluded proper tamping and compacting the bell, particularly laterally exteriorly of the reinforcement and especially when, as is desirable, the reinforcement comprises a solid metallic cylinder disposed substantially intermediate the thickness of the bell end wall.

The general object of this invention, therefore, is to provide new and improved apparatus for tamping reinforced bells on tamped bell and spigot concrete pipe.

A further object of this invention is to provide new and improved apparatus for effectively and efficiently tamping the bell end of reinforced bell, tamped concrete pipe and more particularly for tamping and compacting such a bell end exteriorly of the reinforcement.

Other objects of this invention include the provision of improved apparatus for tamping the bell end of reinforced bell, tamped concrete pipe, which is efficient and economical in operation; which is economically manufactured and installed; which may be used with and mounted on existing apparatus without interfering with the normal use and function thereof; which effectively and efficiently compacts the reinforced bells, exteriorly of the reinforcement, to increase and improve the density and strength thereof; which effectively works and cooperates with and in conjunction with the bell packers now commonly used on tamped concrete pipe forming apparatus to form and provide an efficient, strong bell end on reinforced bell, tamped concrete pipe; which is easily used by unskilled labor; which does not lengthen the manufacturing or pouring process; and, which does not, itself, induce or necessitate further or additional steps in the manufacture of reinforced bell, tamped concrete pipe.

Another object is to provide a new and improved reinforced bell and spigot concrete pipe.

These and other objects and advantages of this invention will become apparent in the specification, claims, and accompanying drawings, wherein:

FIGURE 1 is a broken schematic elevation view, partly in section, with certain parts omitted, of apparatus for producing tamped concrete pipe having associated therewith apparatus, for compacting the bell end of reinforced bell, tamped concrete pipe, embodying a preferred form of this invention;

FIGURE 2 is a partial top plan view of the apparatus shown in FIGURE 1;

FIGURE 3 is a partial elevation view on an enlarged scale of a portion of the apparatus shown in FIGURE 1;

FIGURE 4 is a view taken substantially along the lines 4—4 of FIGURE 2 with certain parts rotated into alignment for clarity, this view embodying a preferred form of the invention.

An apparatus for producing tamped bell and spigot

concrete pipe is indicated generally at 1 in FIGURE 1 and includes a form and core assembly, indicated generally at 2, see FIGURES 1 and 3, and a plurality of tamper machines, indicated generally at 4, only one of which is shown in FIGURE 1. As shown in FIGURE 2, two tamper machines 4 are conventionally embodied in apparatus 1 and are disposed at diametrically opposed portions of the form and core assembly 2.

The form and core assembly 2 of the apparatus 1, comprises a frame 6, see FIGURE 3, which is supported on a suitable foundation and is at least slightly more than twice as high as the length of the longest pipe to be produced in the apparatus. The frame 6 defines and forms opposed vertical track members 7 upon which a transversely extending cross-member or core lift beam 9, having suitable wheels 10, is mounted and supported for reciprocal vertical movement. The cross-member 9 is selectively raised and lowered along the track members 7 by suitable means such as, for example, hydraulic motors 11, each having a piston 12, which retracts to pull downwardly on the associated belts 13 to raise the cross-member 9 and extends to release the tension on belt 13 and permit the cross-member 9 to be lowered. In this regard, the belts 13 are fixed to the member 9 at joints 130, and pass through piston reels 132 and fixed guide reels 134, respectively.

The cross-member 9 is nonrotatably supported on and relative to the track members 7, and, in turn, supports and carries an inner form or core 14. The core 14 is formed of metal or other suitable material, has a height at least equal to the length of the pipe section to be produced thereon, and has an exterior diameter equal to the interior diameter of the spigot and shank of the pipe to be produced thereon. The core 14 is nonrotatably supported on cross-member 9 and the length of the track members 7 is sufficient so that the core 14 may be raised completely out of the newly formed pipe section when it is desired to remove the pipe section from the apparatus 1.

The form and core assembly 2 also includes a bottom assembly or table indicated generally at 15 (FIGURE 1) and an outer form 17. The bottom assembly or table 15 is supported by pin 18 in a suitable driving apparatus (not shown) so as to be rotatable thereby and is adapted to support the core 14 and the form 17 so that the core 14 remains stationary and the form 17 is rotated with the bottom assembly. The outer form 17 defines and forms the outer wall of the pipe section, albeit when the exterior wall of the spigot end is tapered, the taper may be formed by a portion of the bottom assembly 15, as shown in FIGURE 1.

When the tamped pipe is to be reinforced, a suitable reinforcing means, such as wire mesh 20, is disposed between the core 14 and the form 17 and rests upon and is rotated with the table 15.

The form 17 is split longitudinally so as to have half sections which may be separated laterally, so that the newly formed pipe can be removed from the apparatus.

As pointed out above, tamped concrete pipe is formed from an extremely thick mud or slurry having only about six percent moisture content and as a consequence, the concrete, when poured, is dense and flows only slightly. Accordingly, when tamped pipe is manufactured simply pouring the concrete into the form is not enough. It must also be mechanically displaced, tamped or compacted into the forms to form an extremely dense concrete having a high strength.

To this end, the apparatus 1 also preferably includes two tamper machines 4, FIGURES 1 and 2. Each tamper machine comprises a suitable track means 22 upon which tamping means 24 is operatively mounted for selective reciprocal movement so that the tamping means 24 may be moved into proper alignment with the forms, depending on the size pipe to be produced.

The tamping means 24 includes one or more tampers or sticks 25 which are adapted to extend into and between the forms 14 and 17 on both sides of the reinforcing mesh 20 so as to insure that all of the concrete deposited within the form is compacted. The tamping means 24 also includes a friction clutch 27, which engages and supports the tampers with a frictional force of predetermined magnitude so that the tampers are displaced upwardly through the clutch when a force equal to or greater than a predetermined minimum is exerted on the lower extremity of the tamper. Such a clutch 27 is well-known in the art, the structure thereof forming no part of the present invention. Tampers 25 are slid within and are supported and guided for vertical motion by upper and lower guides 28 and 28', respectively. Tampers 25 are reciprocated by the clutch 27 by means of a crank arm 30 and an eccentric drive 31, which, in turn, is driven by motor 33 in a conventional manner. The sticks of tampers 25 have shoelike members, not shown, at their lower extremities, which engage upon, compact and tamp the concrete as it accumulates within the forms.

By way of example, the tampers 25 are conveniently reciprocated at approximately 600 strokes of about 4 1/4 inch length, per minute, and deliver a 300-pound blow to the concrete. As the concrete drops within and between the forms, the tampers 25 are reciprocated so as to push and compact the concrete, thereby increasing its density and insuring that the forms are fully and completely filled. As the level of the concrete rises with the forms, the tampers 25 meet increasing resistance to their reciprocal motion and slip or retreat upwardly through the clutch 27 coincident with the rise in the level of the concrete within the forms. Thus the entire mass of concrete is tamped and compacted as the forms are filled, and no voids remain in the completed section.

If desired, only one tamper machine 4 need have tamper sticks 25 and shoes (not shown) on both sides of the reinforcement 20, while the other need have a stick and a shoe on the outside of the reinforcement only.

The tampers are in fixed positions relative to the form and core assembly 2 and frame 6 and are brought into contact with all of the concrete by the rotation of the table 15, which not only rotates the outer form 17 and reinforcement 20 but, also, the concrete deposited within the form, which slips and slides relative to the fixed core 14.

The rate of rotation of the table 15 depends upon the size of the pipe being made, varying from a rate of 8 r.p.m. for 60-inch diameter pipe to 45 r.p.m. for a 12-inch diameter pipe and being chosen so that the lineal speed of a predetermined point on the pipe being formed is approximately 135 feet per minute.

The bell end of the pipe, which, as noted above, is of larger internal diameter than the rest of the pipe, is formed by means of one or more, and preferably two, bell packers 34, see FIGURES 1, 2, and 4. The bell packers 34 are adapted to exert a lateral pressure upon the newly poured concrete to form the groove or internal configuration of the bell end. As best shown in FIGURE 4, each bell packer 34 is fixedly secured, as by welding or other suitable means, to the core 14 and comprises a channel-like member having a lateral wall 36 which curves outwardly and rotationally rearwardly from the core, and has a vertical shape at its rearward end which is complementary to and forms the interior lateral wall of the bell end of the pipe. Bell packer 34 also includes a bottom wall 37 which forms the shoulder of the bell end, and a top wall 39. Each bell packer 34 pushes and compacts concrete laterally so as to form and shape the bell end to tamp and provide a greater density in the bell than would occur without some compaction being effected upon the concrete as the same is poured and the pipe bell is formed.

As mentioned, two packers 34 are conveniently used in each apparatus and one of these is usually disposed

rotationally immediately after the feeder 40, FIGURE 2, by which the concrete is deposited between the forms 14 and 17, and the other diametrically opposite the first.

The apparatus 1 also includes means, not shown, for lifting the concrete to the feeder 40.

In operation, to form tamped concrete pipe, the core 14 is lowered so as to rest upon the table 15, the outer form 17 is positioned as shown in FIGURE 1, and the reinforcement 20 is disposed intermediate core 14 and form 17. The tamper machines 4 are then actuated to position the sticks 25 so that the tamping shoes are in the correct position relative to the forms and core and the sticks are lowered so that the shoes are adjacent the table.

The concrete is then admitted to the form through the feeder 40 and the tampers and the table 15 are actuated so that the table rotates and the tampers compact and impact the concrete as it falls between the forms 14 and 17, causing the same to flow into position and compacting it into a denser mass than would otherwise be obtained. As explained above, rotation of the table rotates the form 17, reinforcement 20 and newly poured concrete relative to stationary core 14 and the tampers, and as the level of the concrete rises between the forms, the increased resistance met by the sticks 25 causes the same to slip upwardly through the friction slip clutch 27 until the entire length of the pipe is formed. When the level of the concrete reaches the bell end of the pipe the packers 34 displace and exert a lateral pressure upon the concrete, thereby compacting the same laterally to form the interior of the bell and provide a bell of increased density.

Once the pipe forms are filled completely to the top the bell is formed, the tamper machine and table are stopped and within the matter of a minute or so the outer form is opened, the core withdrawn, and the new pipe sections removed to the curing room for proper seasoning.

All of the above is old in the art and, per se, forms no part of the present invention.

It has been customary in the past, when forming reinforced tamped concrete pipe to terminate the wire mesh reinforcement 20 short of the bell end of the pipe so that the bell packer 34 can form the bell. Recently it has been found desirable, as pointed out above, to provide also a metal reinforcement in the bell end of the pipe.

Of necessity, this reinforcement is offset radially from, and has a larger diameter than, the reinforcement 20, which extends longitudinally through the spigot and shank of the pipe. Such reinforcement is indicated at 44, in FIGURE 4, and preferably comprises a solid metallic cylinder having a diameter intermediate the interior and exterior diameters of the bell end of the pipe section.

When such reinforcement is used in tamped concrete pipe, the bell packer 34, while performing the necessary function of forming the interior of the bell end thereof, cannot exert a lateral pressure through the reinforcement to the concrete deposited laterally outwardly thereof, and as a consequence, the bell packer 34 does not pack, compact or otherwise intensify the density of the concrete laterally outwardly of the reinforcement. The concrete in the bell end, therefore, is not uniform and does not have the strength and other characteristics desired.

This invention comprises means adapted to be mounted and supported on the apparatus 1 and more particularly on the lift beam or cross-member 9 which compacts and tamps the concrete laterally outwardly of the reinforcement 44 and is also useful for co-acting with the bell packers of an ordinary, tamped concrete, pipe forming machine to form an improved bell end having greater strength and density than has been obtained in the past with prior art machines and apparatus as described above.

Such apparatus is indicated generally at 45 in FIG-

URES 1 and 4 and is mounted on the beam 9 so that the form 17 and the pipe section being poured are rotated relative thereto. The apparatus 45 comprises driving means adapted to engage the outer form 17 and to be activated by the rotation thereof and vertical packer means, adapted to be driven by said driving means and adapted to contact, roll upon and compact vertically the concrete in the bell, and particularly the area laterally outwardly of the bell reinforcement, as it is poured and rotated or displaced past the apparatus 45 by the rotation of the table 15.

Referring to FIGURE 4, the apparatus 45 preferably comprises a yoke or supporting member 47. The yoke 47 rotatably supports a driving wheel or roller means 48 which is selectively driven by engagement with the outer form 17, and a vertical bell packer roller or compacting means 50, which is adapted to engage the concrete to compact the same, and is driven by the driving wheel or by engagement with the compacted concrete.

The driving roller 48 has a smaller diameter than the compacting roller 53 and has a width such that it may continually and easily ride upon and be driven by frictional engagement with the form 17 as the form 17 is rotated relative to the apparatus 45 by the table 15. The compacting roller 50 has a somewhat larger diameter than driving roller 48, as mentioned, and has a width substantially equal to or slightly larger than the distance between the outermost point 62 (FIGURE 2) of the wall 36 of the bell packer 34 and the interior of form 17 to the end that the compacting roller engages and pushes, flows, compacts and exerts a vertically downward pressure upon all of the concrete forming the completed bell.

Preferably, the rollers 48 and 50 comprise a single unitary member, indicated generally at 51, the member 51 being rotatably supported by means of bearings 53, mounted on a shaft 54, which extends through oppositely disposed apertures 56 in yoke 47. Shaft 54 is preferably threaded as at 57 and detachably secured in yoke 47 by means of nut 59. When necessary, one or more washers 60 may also be disposed about shaft 54 in order properly to position member 51.

Alternatively, it is not without the scope of this invention to fixedly secure the member 51 to a shaft which is rotatably supported in the yoke 47 or to form the driving roller 48 and the vertical bell packer roller 50 as separate cylindrical members fixedly secured to a common shaft, which is, in turn, rotatably supported in yoke 47.

The rollers 48 and 50 are positioned on and relative to the form 17 by means of a suitable motor 63, which is conveniently fluid actuated as by air or liquid. To this end, the yoke 47 is welded or otherwise secured to an arm 65, and the arm 65 is eccentrically mounted on a shaft 66 of the motor 63, and is thereby actuated to raise and lower rollers 48 and 50, as desired into and out of engagement with the form 17 and the concrete, respectively.

The apparatus 45 also includes a base plate 67 (see FIGURE 2) which is bolted or otherwise secured to the cross-member 9. The base plate 67 is preferably detachably and adjustably secured to the cross-member 9 so that the apparatus 45 may be adjusted radially, relative to the form and core assembly 2, along the cross-member 9 so as to be properly positioned for forming and compacting the bell ends of pipes of various predetermined sizes and diameters. The base plate 67 is, also, preferably provided with an arcuate slot 68 through which one or more bolts 70, by which the base plate is secured to the cross-member 9, extends. The slot 68 permits the base plate and the apparatus 45, of which it is a part, to be rotated angularly relative to cross-member 9 to adjust the apparatus 45 and position the rollers 48 and 50 so that they are tangential to the form 17, regardless of the diameter and size of the pipe section being formed. Thus, the base plate 67 is secured to cross-member 9 so as to be adjustable radially angularly in accordance with the size of the particular pipe

section to be formed by loosening the bolts 70 and sliding the base plate relative thereto along the slot 68.

Preferably, two apparatus 45 are used in each apparatus 1 at opposite ends of the cross-member 9, as shown in FIGURE 2.

Also, the vertical bell packers 45 are so positioned, that the point of contact between the poured concrete and each compacting roller 59 is substantially radially aligned with the point of contact between the adjacent bell packer 34 and the concrete. The concrete is, therefore, simultaneously subjected to the vertical force of the roller 59 of the apparatus 45 and the lateral force of the bell packer 34.

When the size of the pipe to be formed on the apparatus 1 is changed, the rollers 48 and 50 are also conveniently and preferably changed in order to properly co-act with the particular forms 14 and 17 being used and pipe section being formed. To this end, the rollers are easily replaced by loosening the nut 59, removing the shaft 54, substituting the new rollers for the old, and reassembling the shaft in the yoke.

The motor 63 preferably delivers a force of about 1000 pounds to the member 51, which, in turn, compacts and engages the form and/or the concrete with a force of approximately 500 pounds. Thus the pressure of the newly poured concrete cannot raise the member 51 and the concrete is displaced thereby in the manner set forth above.

In operation, it is preferred that as the level of concrete within the form approaches the level of the bell, the motor 63 is actuated to cause the roller 48 to engage and ride upon the rotating form 17, which rotates roller 48 and thereby compacting roller 50. Roller 50 pushes and displaces the newly poured concrete downwardly into the bell. Once the level of the concrete within the bell cavity is sufficient high and the concrete has been compacted sufficiently so that the compacting roller 50 is turned by frictional engagement with the concrete itself, the motor 63 is actuated to withdraw the member 51 so that the roller 48 is approximately $\frac{1}{16}$ of an inch or so above the form 17, and out of contact therewith. The entire pressure of the motor upon the member 51 then bears upon the newly formed concrete. The table 15 is then rotated approximately one revolution to complete formation of the bell.

In order to provide greater flexibility and utility for the apparatus 45, the motor 63 may be provided with an accumulator. In such an instance, if the roller 53 binds on the form or engages a rock or other foreign or deleterious matter in the concrete, the increased pressure resulting from the incompressibility thereof, can overcome the pressure in the accumulator thereby permitting the member 51 to lift or raise until the obstruction is passed.

The apparatus 45 and disclosed method may also be advantageously used to form tamped concrete pipe which does not have a reinforced bell, as it cooperates with the bell packer 34 to provide a bell of unexpectedly increased density and greater strength than is obtained by the use of a conventional bell packer alone.

From the foregoing description of a preferred form of this invention it will be evident that there has been provided a new and improved method and apparatus for compacting and increasing the density and strength of the bell of tamped concrete pipe, and more particularly for tamping, compacting and properly forming the laterally outwardly portions of the bell ends of reinforced bell tamped concrete pipe to provide a notably improved product. Such method and apparatus is economically used and manufactured. It is readily adapted for use on conventional tamped concrete pipe machinery now in existence, and does not in any way interfere with the use and operation of the other parts and portions of the machinery upon which it is mounted or adapted for mounting.

It is to be understood that apparatus, method, and product embodying this invention may be used with other

types and forms of tamped concrete pipe apparatus and that other types and forms of tamped concrete pipe may be adapted for use while embodying this invention.

Those skilled in the art will appreciate that various changes and modifications can be made to the invention herein described and disposed without departing from the spirit and scope thereof. The essential features of the invention are defined in the appended claims.

I claim:

1. In apparatus for manufacturing bell and spigot tamped concrete pipe, including a stationary core, a cross-member supporting the core, a rotatable outer form having a top edge and a lateral bell packer secured to said core and having side and bottom walls adapted to form the inside wall and shoulder of the bell end of a pipe section, the improvement of a vertical bell packer for compacting the concrete vertically, laterally outwardly of said inside wall, said vertical bell packer comprising a base plate, a motor mounted on said base plate, support means mounted on said motor and adapted to be actuated thereby, a roller means carried by said support means and having an edge adapted to engage upon said top of said outer form and to be driven by engagement therewith when said outer form is rotated, second roller means carried by said support means having an edge of greater diameter than said first roller means for compacting the concrete in the bell laterally outwardly of said inside wall, means operatively interconnecting said roller means, means for detachably securing said base plate to said cross-member whereby said base plate is radially and angularly adjustable on said cross-member and relative to said core and outer form, said motor means including means to exert a predetermined pressure on said roller means to hold said roller means in a predetermined position, and to raise and lower said roller means selectively relative to said outer form.

2. In apparatus for manufacturing bell and spigot tamped concrete pipe, including a stationary core, a cross-member supporting the core, a rotatable outer form having a top edge and a lateral bell packer secured to said core and having side and bottom walls adapted to form the inside wall and shoulder of the bell end of a pipe section, the improvement of a vertical bell packer for compacting the concrete vertically, laterally outwardly of said inside wall, said vertical bell packer comprising a base plate, a motor mounted on said base plate, support means mounted on said motor and adapted to be actuated thereby, a roller member rotatably mounted on said support means, said roller member having a first cylindrical portion having an edge for engagement upon said top of said outer form and to be driven by engagement therewith when said outer form is rotated and a second cylindrical portion having an edge of greater diameter than said first portion and a width substantially equal to the distance between said lateral bell packer and said outer form for compacting the concrete in the bell laterally outwardly of said inside wall, means detachably securing said base plate to said cross-member whereby said base plate is radially and angularly adjustable on said cross-member and relative to said core and outer form, said motor including means to exert a predetermined pressure on said roller member to hold said roller member in a predetermined position, and to raise and lower said roller member selectively relative to said outer form.

3. In apparatus for manufacturing bell and spigot tamped concrete pipe including a stationary core, a cross-member supporting the core, a rotatable outer form having a top edge and a lateral bell packer secured to said core and having side and bottom walls adapted to form the inside wall and shoulder of the bell end of a pipe section, the improvement of a vertical bell packer for compacting the concrete vertically, laterally outwardly of said inside wall, said vertical bell packer comprising a base plate, a motor mounted on said base plate, a support means mounted on said motor and adapted

to be actuated thereby, a roller member rotatably mounted on said support means, said roller member having a first cylindrical portion with an edge for engagement upon said top of said outer form and to be driven by engagement therewith when said outer form is rotated and a second cylindrical portion having an edge of greater diameter than said first portion and a width substantially equal to the distance between said lateral bell packer and said outer form for compacting the concrete in the bell laterally outwardly of said inside wall, said base plate having an arcuate slot therein and means, a portion of which extends through said slot, for detachably securing said base plate to said cross-member, said base plate being radially and angularly adjustable on said cross-member and relative to said core and outer form, said motor including means to exert a predetermined pressure on said roller member to hold said roller member in a predetermined position, and to raise and lower said roller member selectively relative to said outer form.

4. In apparatus for manufacturing bell and spigot tamped concrete pipe including a stationary core, a cross-member supporting the core, a rotatable outer form having a top edge and a lateral bell packer secured to said core and having side and bottom walls for forming the inside wall and shoulder of the bell end of a pipe section, the improvement of a vertical bell packer for compacting the concrete vertically, laterally outwardly of said inside wall, said vertical bell packer comprising a base plate, a motor mounted on said base plate, a connecting arm on said motor and adapted to be actuated thereby, said arm having an end remote from said motor, a yoke having spaced side members secured to said arm, a shaft detachably mounted on said spaced side members,

20

25

30

a roller member rotatably mounted on said shaft, said roller member having a first cylindrical portion with an edge for engagement upon said top of said outer form and to be driven by engagement therewith when said outer form is rotated, and a second cylindrical portion having an edge of greater diameter than said first portion and a width substantially equal to the distance between said lateral bell packer and said outer form for compacting the concrete in the bell laterally outwardly of said inside wall, said base plate having an arcuate slot therein and means, a portion of which extends through said slot, for detachably securing said base plate to said cross-member, said base plate being radially and angularly adjustable on said cross-member and relative to said core and outer form, said motor including means to exert a predetermined pressure on said roller member to hold said roller member in a predetermined position, and to raise and lower said roller member selectively relative to said outer form.
